HEAT EXCHANGER

Richard F. Adams, Goshen, Ind., assignor to Olin Mathie-
son Chemical Corporation, East Alton, Ill., a corpora-
tion of Virginia

Application January 17, 1956, Serial No. 559,552

7 Claims. (Cl. 257—244)

This invention relates to a heat exchanger and more specifically to a pump, blower or fan heat exchanger unit.

It is an object of this invention to provide a novel and improved fluid moving device, particularly a centrifugal fluid moving device, with a heat exchanger of sturdy, corrosion resistant, economical construction. Another object is the provision of an impelled or centrifugal fluid heat exchanger device capable of either removing or imparting a considerable amount of heat to the fluid medium with high efficiency and thereafter distributing the affected medium desirably. Other objects and advantages will become apparent from the detailed description and accompanying drawing in which:

Fig. 1 is an elevational side view partially in cross section corresponding to a view on line I—I of Figure 2 and showing one embodiment of this invention;

Fig. 2 is a cross sectional elevational view of the embodiment of Figure 1 including the parts broken away; taken on line II—II of Figure 1;

Fig. 3 is an elevational side view showing another embodiment of this invention partially in cross section;

Fig. 4 is a semi-diagrammatic view in cross section taken on line IV—IV of Figure 3 including the parts broken away; and

Fig. 5 is a plan view on a somewhat enlarged scale of a portion of the surface of a convolution of the embodiment of Figures 3 and 4.

In accordance with this invention there is provided a novel combination of primer mover, fluid impeller and heat exchanger adapted to accept the impelled fluid on one side and discharge it directionally on the other after desired heat exchange has been accomplished. This construction constitutes a unit capable of affecting the heat content of the moving fluid in transit.

The present invention contemplates the manufacture of a heat exchanger shell or panel containing a great number of integral, but individually distinct, heat exchanger fluid tubes of relatively small cross section and also having openings in the panel between the tubes. The method involves providing a cavitated panel from flat component sheets which, with intervening stop-weld material in a pattern including parallel spaced stripes, have been unified as by rolling at sufficient pressure except where prevented by the pattern and then distended, shaping the panel to a suitable open-ended tubular shell by bending to a circular or spiral configuration, and also slitting the bonded or web portion of the panel between the conduits without interrupting or puncturing the conduits. The curvilinear heat exchanger shell provides confinement of the unaffected fluid adapting it to desired heat exchange in circulation. The slits provide openings for the desired circulation of air or other fluid medium from the interior of the shell to its exterior. Furthermore, the slit bonded web portion between the parallel conduit portion is additionally shaped to form vanes which impart desired directionality and turbulence to the air passing through the shell.

In the embodiment of Figures 1 and 2, the apparatus

2

of this invention consists in general of an electric motor 1, its extended shaft 2, the fluid moving blades 3, and a surrounding casing 4 with fluid outlets 11, and also a self-contained heat exchanger fluid passageway system 6 for circulation of water, steam, refrigerant, or other suitable heat exchanger fluid for affecting the gas or liquid medium impelled through outlets 11.

Casing 4 is a pressure unified panel made by the method of the type disclosed in U. S. Patent 2,690,002, issued September 28, 1954, to L. H. Grenell. This casing is a web-like structure wherein the webs serve to not only connect the several tubes or passages 8 into a strong integral structure free from joints but also serve as heat dissipating or absorbing surfaces.

However, for the purpose of this embodiment of the invention the pressure welded panel is formed to a circular or curvilinear shape as shown in Figure 2 and the free ends of the panel are joined together in any suitable way as shown at 7. Moreover, the hollow or conducting tube portions of the heat exchanger passageway 6 are formed at one end of the cylinder into a grid-work consisting of parallel spaced passages 8 the ends of which are inter-connected at one end by an inlet header passageway 9 and at the other end by an outlet header passageway 10. Any suitable inlet tube 35 makes connection with inlet header passageway 9, while outlet tube 36 makes connection with the outlet header passageway 10. In between the web portion of the parallel cooling or heating passageways 8, the web portion of 30 the panel is provided with openings 11 with directional vanes 12 adjacent each opening, and formed as an integral part of the panel or casing 4. This arrangement provides a circular array of openings 11 in alternation with passages 8. One end of the cylinder adjacent 35 the grid-work is open at 13 to form an intake for the unit. At the other end, the centrifugal panel 4 is solid and constitutes a flange 14 for mounting the panel on motor 1. Thus, the major part of the casing 4 is utilized as a heat exchanger surface. On one side of the motor 40 there is an extended shaft 1 projecting into the interior of the casing 4 and having mounted thereon the fluid impellers 3 in desired proximity with the passages 8 and the openings 11.

In operation, the fluid to be moved is drawn in at 45 the intake 13 and driven out of the discharge openings 11 after being put into desired turbulence and directionality with respect to the heat exchanger fluid carrying passageways 8 by means of the directional vanes 12. These also impart directionality to the fluid so 50 that a wide-spread and substantially uniform distribution is obtained.

In the embodiment of Figures 3 and 4 the unit is constituted of a motor 15 having opposite shafts 16 and 17, each carrying an impeller 18 and 19 respectively, 55 and a surrounding heat exchanger casing 20 which as in the previous embodiment is an apertured pressure welded panel having dilated or fluid pressure distended heat exchanger passageway 21 running circuitously through panel 20. However, in this embodiment as 60 shown in Figure 4 the panel or casing 20 is convolutely wound in spiral form so as to provide a great number of layers and consequently greatly increase the heat exchanger capacity of the unit. While the spiral form of panel 20 is shown, it will be understood that the heat exchanger casing 20 may consist of a number of concentric cylindrical panels fitting one within another and each having suitable inlet and outlet connections for the heat exchanger fluid to be circulated in the respective passageways of the panels constituting the casing. In 65 this embodiment as shown in Figure 3 the heat exchanger circuit 21 is serpentine and includes a number of heat exchange tubes or loops 22 which are in parallel 70 with the fluid moving blades 3.

with each other. Between the tubes, as in the previous embodiment, the webbing of the panel has suitable discharge openings 23. The desired turbulence and directionality is imparted to the fluid being moved by shaping each panel web portion adjacent the tubes of each loop at an oblique angle to the plane of tangency with the panel at the tubes 22. Thus, each of the heat exchanger tubes 22, in effect, is formed in a suitably sloped vane 24 disposed between the discharge openings 23. Panel 20 has an inner axially extending end and a similarly extending outer end containing the inlet terminal 25 and the outlet terminal 26 respectively of the fluid circuit 21. Here any suitable connection with the unit is made with a heater or cooler fluid source. Casing 20 is mounted in any suitable manner for support and bearing purposes together with motor 15 and the shaft extensions 16 and 17.

In operation impeller blades 18 and 19 draw air, for example, into the intake openings 28 and 29 (Figure 3) and drive it through the many discharge openings 23 of the panel 20 where desired turbulence and directionality is imparted. The temperature of the air is thus desirably raised or lowered during its passage through the encasing panel 20.

In the enlarged view of Figure 5, the surface structure of the sheet of metal forming the convolutions of the embodiment of Figures 3 and 4 is shown in a flat plane in somewhat greater detail and clarity.

Preparation of the structure of casing 4 of the embodiment of Figures 1 and 2 and the structure of the casing 20 of the embodiment of Figures 3 and 4 is done generally in accordance with the method of aforementioned U. S. Patent No. 2,690,002 by rolling together a pair of component, initially separate sheets with the passageway pattern of weld preventative therebetween. All are rolled at least to a suitable minimum reduction in thickness. This produces a metal structure having at least a strong metallurgical type of bond between the component sheets at all interfacial areas not initially protected by weld-preventing material and finally subjected to inflation. Upon completion of such pressure unification, under suitable conditions, practically no interface between the initial component sheets of metal such as copper, aluminum, steel and the like, or their alloys, is discernible; but in any event an excellent bond is obtained around the pattern. Consequently, the resultant panel may be manipulated in the same manner as a single sheet initially rolled to the same thickness as the panel, but with the advantage of being inflatable. It will be appreciated that this hollow conduit or heat exchange structure is free from joints having extraneous bonding material at which corrosion ordinarily begins.

The bonded web areas of the panels between the parallel spaced liquid conduits are perforated as by punching or slitting, preferably after inflation, and the web of each panel is at the same time or afterward folded, drawn or otherwise deformed to provide a vane. Thus, the webbing between passageways 8 of the embodiment of Figures 1 and 2 is slit to make opening 11 and the slit web is shaped to form vanes 12. Similarly the webbing between passageways 22 of Figures 3, 4 and 5 is slit to make openings 23 and there are formed vanes 24 adjacent the openings 23. Each of the casings 4 and 20 is then shaped to provide the curvilinear shell configuration shown for the particular embodiment.

From the foregoing description, those skilled in the art will readily understand not only the construction of the device of this invention but will also appreciate that it accomplishes the objects of the invention. The construction of the unit is such that it can be readily installed and can be operated without need for frequent repair. Furthermore, the construction is such that the unit is relatively free from joints and extraneous fastening materials so that it is adapted to resist corrosion even with

highly corrosive atmospheres or liquids. The unit is adapted for efficient heat exchange and distribution.

While the invention has been described with particular reference to embodiments now believed to be more advantageous, it will be understood that those skilled in the art may make changes and modifications without departing from the spirit and scope of the invention as set forth in the appended claims.

Having thus described the invention, what I claim and desire to secure by Letters Patent is:

1. A heat exchanger for a centrifugal fluid medium comprising a tube-shaped panel at least one end of which is shaped to surround a central opening for intake of said medium, said panel having distended double-walled sections forming the walls of interconnected internal heat exchange fluid passageway portions including some extending longitudinally and spaced from each other around the circumference of said panel, web section integral with said double-walled sections, and at least one transfer opening through the panel in each of the undistended web sections between said passageway portions, said transfer openings at the edge thereof being provided with vanes integral with said web sections to constrain said fluid medium to pass tangentially and outwardly through said panel in more efficient heat exchange relationship with said web sections and passageway portions.
2. The heat exchanger of claim 1 wherein the panel is convolutely wound to provide a plurality of layers of the panel.
3. A heat exchanger for a centrifugal fluid medium comprising a plurality of superposed tubular sheet panels coaxially disposed in layers around a central space having at least at one end an opening for intake of said medium, means in said space for impelling said medium, said panels having distended double-walled sections forming the walls of interconnected internal heat exchange fluid passageway portions at least some of which extend longitudinally and are spaced from each other around the tubular plane of each of said panels and at least one transfer opening through each panel in each of the undistended web sections, between said passageway portions, each panel adjacent said transfer openings being bent to constrain said fluid medium to pass tangentially and outwardly through said panel in heat exchange relationship with said passageway portions.
4. The heat exchanger of claim 1 wherein substantially all of the section of the panel containing the spaced passageway portions is turned at an angle to the adjacent similar sections of the panel.
5. A heat exchanger for a centrifugal fluid medium comprising a cylindrical sheet metal panel around a central space one end of which has an opening for intake for said medium, said panel having distended double-walled sections forming the walls of interconnected internal heat exchange fluid passageway portions some of which extend longitudinally and are circumferentially spaced from each other in the curvilinear plane of said panel, said panel having a transfer opening in each of the undistended web sections between said passageway portions, one side of said web sections adjacent each of said transfer openings being bent at an angle to said web section to form a vane for constraining said impelled first fluid medium to pass spirally in a predetermined direction through said panel between each of said vanes and corresponding passageway portion in heat exchange relationship with the fluid in said passageway portions.
6. A heat exchanger for a centrifugal fluid medium comprising a curvilinear sheet metal panel convolutely wound upon itself to provide a plurality of superposed layers around a central space both ends of which have an opening for intake of said medium, said panel having distended double-walled sections forming the walls of interconnected internal heat exchange fluid passageway portions some of which extend longitudinally and are circumferentially spaced from each other in the curvilinear

plane of said panel and at least one transfer opening through the panel in each of the undistended web sections between said spaced passageway portions, said web sections adjacent said transfer openings being turned to form vanes to constrain said fluid medium to spiral outwardly through said panel in heat exchange relationship with said web sections and passageway portions, and a pair of fluid impellers disposed in said central space for drawing said medium in through said end openings and discharging said medium outwardly through the transfer openings of said panel.

7. A heat exchanger for a centrifugal fluid medium comprising at least one annular panel at least one end of which is shaped to surround a central opening for intake of said medium, said panel having distended double-walled sections forming the walls of interconnected internal heat exchange fluid passageway portions extending in spaced relationship with respect to each other around the circumference of said panel, undistended web sections between said passageway portions integral therewith, and

at least one transfer opening through the panel in each of said web sections, said transfer openings at the edges thereof having vanes integral with said web sections to constrain said fluid medium to pass tangentially and outwardly with respect to said panel in efficient heat exchange relationship with said web sections and passageway portions.
